METHOD OF MAKING DENTAL TRAYS

Sody Salabes, Baltimore, Md.

Application November 8, 1935, Serial No. 48,934

1 Claim. (Cl. 204—6)

The present invention relates in general to a method of making dental trays for taking oral impressions as a preparatory step to making dentures and particularly to impression trays with 5 water cooled walls.

One object of the invention is to provide a quick cooling tray of less bulk and of less weight than those in present use, so as to facilitate positioning of the tray in the patient's mouth and to 10 lessen discomfort to the patient.

Another object is to provide a tray having positive cooling means, so that the impression material will be properly and quickly cooled. The manner of cooling the oral parts and the tray by 15 means of a spray of cool water projected into the patient's mouth is unsatisfactory, uncertain and untidy. The cooling of the tray of this invention is provided for by the circulation of a cooling medium throughout hollow tray walls.

Another object of the invention is to provide for 20 bracing the thin tray walls to strengthen them and to provide locking means for retention of the impression material in the tray when in use.

Other objects and advantages of the tray will be apparent from the following description in 25 connection with the accompanying drawing which illustrates a preferred embodiment of the invention, it being understood that detail changes and variation in shape may be made without departing from the scope or spirit of the invention.

In the drawing:

Figure 1 is a view, in perspective, of a tray made by the method of the invention, showing inlet and outlet connections for the cooling medium.

Figure 2 is an enlarged fragmentary view in section taken on line 2—2 of Figure 1.

Figure 3 is an enlarged fragmentary view in 40 section taken along line 3—3 of Figure 1.

Figure 4 is a side elevation of the device illustrated in Figure 1.

The tray shown in Figure 1 is used for taking impressions of part of the oral cavity so that 45 from the impression thus obtained, a denture may be produced which will conform with great precision to the configuration of the part impressed. By denture, in this connection, will be understood such dental appliances as are in general use to replace or provide teeth or parts where they are needed and may take the form of crowns, 50 bridges, entire or partial plates or such other devices as are in use in oral and dental surgery and it is understood that the tray is so fashioned as to

adequately provide for the size and form of the required impression.

The tray walls 10 are hollow and continuous, forming a chamber consisting of outer walls 11 and inner walls 12, joined at their margins, and 5 in spaced relation to each other, the space 13 between them providing for the circulation of the cooling medium. The tubes 14 and 15, respectively, are inlet and outlet connection tubes for the circulation medium. These tubes may be 10 made integral with the tray or they may be fixed in place after the tray is made. These tubes are held in fixed relative position by the brace 16.

The outer wall 11 and inner wall 12 are stiffened and strengthened by means of a plurality of 15 tubulures 17, which are of comparatively small diameter. The walls of the tubulures are continuous with the inner and outer walls of the tray. When the impression material, in a warm plastic state, is pressed in the tray, it fills these 20 tubulures and when the impression material cools and hardens it is locked into position by means of the hardened material in the tubulures, that is to say, when the soft impression material 25 is pressed against the oral part to be modeled the material is also forced into the tubulures and hardening, as it cools, the tray may be removed from the patient's mouth without displacement of the material by the resultant suction action of such removal and without damage to the delicate 30 contours of the impression. Models made from such impressions will very closely approximate to the general configuration and character of the 35 part impressed.

The tubulures 17 may be of simple cylindrical 35 shape or they may be made of truncated conical form to provide for better anchorage. It is understood, however, that the tubulures may be omitted altogether in some trays where they are not desired.

The method of making the trays comprises the 40 following steps:—

A mold for the tray core is first made. This mold may be of any suitable plastic material, plaster of Paris, metal, wood or any moldable 45 material. This mold is made so that it approximates the general form and size of the part of which the impression is to be taken, due allowance being made for the bulk of the impression material itself.

A fusible alloy or material of low melting point 50 is melted and poured into the mold. When this has solidified, which with such materials is generally almost immediately, the molded core is removed from the mold and is ready for the next 55

- step in the process. I have found that Lipowitz' alloy, which is a well known composition of lead, tin, cadmium and bismuth gives an excellent result, although other alloys and suitable compositions may be used. While a mold has been described for casting the core, the core may be made directly from the fusible materials by working, stamping, carving, or other means.
- The alloy core is next pierced with a number of small holes of the order of one sixteenth of an inch in diameter, the purpose of which will be made apparent below. While these holes are not essential to the method, they add to the usefulness, durability and efficacy of the finished tray.
- The cast alloy core is next immersed in an electro-plating bath and thinly plated with a metal which is both tough enough and strong enough to maintain its shape when the tray is completed and in use. I have found copper plating gives an excellent result with light, strong walls, and is both cheap and durable. Other metals such as nickel, chromium, cobalt, silver, and gold or other material may be used. I have found electro-plating of the mold entirely satisfactory, although other plating methods may be used such as dip coating, spraying, swaging or combinations thereof under suitable conditions, and with suitable materials.
- The plating step having been completed the next step is the discharging of the low melting point metal alloy by fusion in a water bath of proper temperature or other bath or by means of heating the tray with the core, above the melting point of the fusible core. This leaves the metallic hollow-walled sheath or shell conforming most closely to the configuration of the core. The walls of the holes referred to above having also been coated in the plating bath, form tubulures in the tray which act as braces passing

through the hollow-walled portion of the tray and also afford means whereby the impression material is anchored to the tray in a satisfactory manner as described above.

The tray is now ready to receive the inlet and outlet connections by means of which the cooling medium to be circulated therethrough is supplied and conducted away. These inlet and outlet connections may be made integral with the tray itself, if desired, by casting a mold for them with the molded core, although it has been found expedient to affix them after the tray walls have been produced. The inlet and outlet openings serve also to permit the discharging of the core material after the plating operation.

Trays made by this method are light-walled, rigid, strong, durable, inexpensive and more satisfactory for the purpose than those used heretofore.

Having thus described the invention, what is claimed is:—

The process of forming a dental tray to fit the oral cavity comprising, forming a core mold material with an electric conducting surface into a required shape for forming a dental tray with openings for inlet and outlet of a cooling medium, providing a multiplicity of small holes therethrough of a size sufficient to produce when deposited upon stiffening members serving to lock and effect rapid cooling of impression material to be used therein, immersing said core in a metal plating bath wherein the material of a higher melting temperature than the material of the core is deposited around said core and the holes therein, then subjecting said coated core to a means for melting said core but not melting said deposited metal thus permitting said core material to escape through said inlet and outlet opening.
